UNITED STATES PATENT OFFICE.

FRANK ELLISON BEST, OF SEATTLE, WASHINGTON, ASSIGNOR TO FRANK E. BEST, INC., OF SEATTLE, WASHINGTON, A CORPORATION OF WASHINGTON.

LOCK COMBINATOR.

Application filed May 9, 1923. Serial No. 637,721.

My invention relates to improvements in lock combinator and the object of my invention is to provide mechanical means for changing the combination of a pin tumbler lock. A more specific object is to provide mechanical means for determining the combination of a pin tumbler lock to correspond to one or more keys that may be inserted in the machine and for filling said lock to fit 10 said keys.

Other and more specific objects will be apparent from the following description taken in connection with the accompanying drawings. In accomplishing the above objects 15 my device performs the following major functions:

1. Ejection of old pins from the lock mechanism.
2. Making new pins to match a certain 20 key or keys.
3. Making of tumbler springs.
4. Delivery of said springs and pins to the lock mechanism.
5. Securing of same in place in the lock 25 mechanism.

In accomplishing the aforesaid and other objects of my invention, I have provided means, the preferred forms of which are illustrated in the accompanying drawings, 30 wherein:

Fig. 1 is a perspective view of the device.

Fig. 2 is a similar view with the key carriage and related mechanism removed and a side door opened.

35 Fig. 3 is a perspective view of the key carriage.

Fig. 4 is a top view of the device.

Fig. 5 is a front elevation of the device.

40 Fig. 6 is an elevation showing the left side.

Fig. 7 is a rear view with the motor portion removed.

Fig. 8 is a section on line 8—8 Fig. 4.

Fig. 9 is a section on line 9—9 Fig. 4.

45 Fig. 10 is a section on line 10—10 Fig. 4.

Fig. 11 is a section on line 11—11 Fig. 5.

Fig. 12 is a section on line 12—12 Fig. 4.

Fig. 13 is a section on line 13—13 Fig. 4.

Fig. 14 is a section on line 14—14 Fig. 9.

50 Fig. 15 is a section on line 15—15 Fig. 4.

Fig. 16 is a detail partly in section and

partly in elevation of the cutter drive.

Fig. 17 is a perspective detail showing the cutter housing.

Fig. 18 is a section thru key carriage unit 55 on line 18—18 Fig. 11.

Fig. 19 is a section thru the key carriage unit on line 19—19 Fig. 11.

Fig. 20 is a section on line 20—20 Fig. 11 showing the escapement teeth and their re- 60 spective positions.

Fig. 21 is a perspective view showing the key holder proper.

Fig. 22 is a detached view in longitudinal cross section on line 22—22 of Fig. 12 showing the spring wire feeding device.

Fig. 23 is a horizontal section taken on line 23—23 Fig. 5 showing a lock core in position for ejecting old pins from said lock core.

70 Fig. 24 shows the same in position for loading new pins into the lock core.

Fig. 25 is a cross section taken on line 25—25 of Fig. 15, showing the slug delivery unit.

75 Fig. 26 is a fragmentary view partly in elevation and partly in cross section on line 26—26 Fig. 6 showing a group of cam followers.

Fig. 27 is a detached isometric view showing certain safety devices.

80 Fig. 28 is another detached isometric view showing parts of mechanism that controls the insertion and removal of the keys from the key holder.

Fig. 29 is a fragmentary view partly in elevation and partly in cross section showing the spring wire and cap feeding means.

85 Fig. 30 is a detached isometric view showing parts of safety devices connected with the pin slug feeding means and parts of devices for operating the pin burring tool.

Fig. 31 is a detached isometric view showing a part of the mechanism for operating the spring wire feed.

90 Fig. 32 is a detached isometric view showing the lever controlling the key carriage escapement.

Fig. 33 is a diagram illustrating the sequence and time of various movements controlled by cams and gears.

100 Fig. 34 is a schematic lay out of the machine.

Similar characters refer to the same or

similar parts throughout the several views.

A base plate 30 supported on legs 31 together with front frame 32 and central frame 33 constitute the principal frame structure of the device.

A source of power 34 through its drive shaft 35, Figs. 8 and 34, drives pin collet stem 36 secured thereto by set screw 37. Pin collet stem 36 has a worm 38 which 10 drives worm wheel 39, integral with cross shaft 40, Figs. 9, 10 and 14.

Cross shaft 40 is supported at the right end by bearing 41 housed in auxiliary frame 42, Figs. 2, 8, 10 and 14. Its left end is 15 supported in bearing 43 housed in screw cap 44, Figs. 6 and 14, which is screwed into central frame 33 by means of spanner in holes 45 and is secured in place by set screw 46.

20 Cross shaft 40 has a worm 47 integral which drives worm gear 48, Figs. 6, 9 and 34, secured to stud 49 of cam drum 50 by pin 51.

Cam drum 50 is supported at the top by bearing 52 mounted on pin 53 of frame 32, 25 Fig. 9.

Cam drum 50 contains a dry disc friction clutch 52, consisting of alternate peripherally and centrally splined plates 53 and 54 secured against rotation to cylinder 55 and stud 49 respectively. Pressure yoke 56 adjusted by screw 57 carrying spring 58 by bearing downwardly on the uppermost plate 53 provides the frictional contact of the pressure plates 53 and 54 and frictionally 30 binds cylinder 55 to stud 49. This makes possible the stopping of the cam cylinder 55 and the various cams carried thereon between two successive cam cycles without shutting off the power by the engagement 35 of plunger 59 with toothed ring 60 keyed to cylinder 55, said ring 60 having a single tooth arranged to engage the plunger 59, Figs. 9 and 27.

A cap plate 61, screwed into base plate 30 40 by means of spanner holes 62, and secured in place by set screw 63, Fig. 6, provides adjustment for and forms the lower support of cam drum 50 through bearing 64.

Cross shaft 40 carries a bevel gear 65 45 meshing with bevel gear 66, Figs. 9, 34 and 14, integral with spur gear 67 mounted on shaft 68, Fig. 7, journaled in bushing 69 and carrying a thrust collar 70, secured on its outer extremity by a taper pin shown by 50 broken lines, Fig. 7. Spur gear 67 drives idler gear 71 integral with a shaft 72, Figs. 4 and 7, journaled in a bushing 73 and carrying a thrust collar 74 on its outer extremity secured by a taper pin 76, Fig. 4.

60 Idler gear 71, in turn, drives escapement drum 84 thru spur ring gear 75 (see Figs. 2, 4, 6, 9 and 11) which is friction bound there- 65 to between shoulder 77 of hollow split stud 78 and washer plate 79. A spring 80, Fig. 9, acting between washer plate 79 and

splined nut 81 puts the frictional tension on gear 75. Adjusting screw 82 operating within hollow stud 78 regulates the position of nut 81 and thereby the frictional tension on gear 75, Figs. 9 and 13.

70 Screw 82 is journaled at 83 to hollow split stud 78 to allow rotation and prevent longitudinal movement. Hollow split stud 78 is closely fitted but not directly secured to escapement drum 84 which it drives thru hollow shaft 85 in end contact therewith secured against independent rotation by keys 86 secured in key ways in the end of hollow shaft 85 and extending into the splits of stud 78. This hollow shaft 85 is secured 75 to escapement drum 84 by set screw 87. Bearings 88 and 89 hold the said members in contact and provide the suspension means for this unit. A screw 90 secured to frame 80 33 supports bearing 89, while spanner nuts 91 and 92 with an intermediate lock washer 93 all of which fit into boss 94 of frame 32, support bearing 88. Hollow shaft 85 carries at its forward extremity a disc 95 having pins 96 which drive pin measuring stepped collar 97 and at the same time allow collar 97 to be adjusted toward or away from disc 95. Cap screw 98 facilitates the securing of disc 95 to hollow shaft 85. Although stepped collar 97 is driven by adjustable connection with disc 95 yet it is supported and guided by spanner nuts 99 and 100 and keyed washer 101.

95 Each revolution of cam drum 50 represents a cycle of the machine in which an old stack of pins with its spring and cap is ejected from the lock core and a new stack of pins with its spring is made to match whatever key or keys are inserted in the machine and delivered, together with a cap to the lock core, (see Figs. 23 and 24).

100 The ejection of the old stack and the re-loading of the lock core is as follows: Ejecting plunger 102 operating in a guide 103 (see Figs. 23, 24, 1 and 2) and actuated by lever 104 ejects stack 105, Figs. 23, through guide 106 into hole 107 and thence by gravity the stack passes down thru the machine to the space below. Guide 106 is flexibly held by spring 108 to frame 32 by screws 110 105. If a new lock core or an already empty lock core is being filled ejecting plunger will operate in the same manner thus making certain that no obstructions remain in the pin receiving holes of the lock core. Subsequently the core carriage 110 with the lock core 111 advances to the new position shown in Fig. 24 and the pin delivery arm 112 with its stack of pins 113 comes into its new position, Fig. 24, having pushed guide 106 115 out of its way, in which position the stack of pins 113 is in alignment with the tumbler hole 114. Simultaneously spring delivery arm 115, Fig. 34, with a newly made spring 116 120 is also brought into register, and cap 117 125 is also brought into register, and cap 130

delivery plate 117 with a cap 118 is brought into proper alignment. Plunger 119 actuated by lever 120 carried in a guide 122 then delivers the pins, spring and cap into the tumbler hole of the lock core in alignment therewith. Inasmuch as the cap is larger than the hole in the core it acts like a cork when forced into place and retains the pins and springs. A spring 121 returns plunger 119 into its original position. Lever 120 (see Figs. 7, 9, 23 and 24) is carried on and is integral with hollow shaft 123 pivoted in frame 33 on screw 124 having a bushing 125. Integral with this lever 120 is a cam follower 126 having a roller 127 in contact with cam ring 128 keyed to cylinder 55 which drives the afore-described mechanism.

Lever 104, Figs. 23, 24, 1, 2, and 5, which operates the ejecting plunger 102 is pivoted on screw 129 secured to block 130 which in turn is secured to base plate 30, and is actuated by cam follower 131, see Fig. 9, having a roller 132 in contact with cam ring 133 keyed to cylinder 55 from which it derives its movement. A spring 134, Fig. 4, connecting the lower end of lever 104 with base plate 30 thru lug 135 secured thereto by screw 136, Figs. 5 and 15, provides a return for the ejecting plunger 102 and its train.

The making of the stack of pins is as follows:

The material is supplied in the form of slugs 137 in magazines 138, Fig. 15. For the length and shape of these slugs see the slug 137 shown in Fig. 25 in the slug delivery arm 147 and in the collet 139 (on the horizontal center line, Fig. 8). The slugs are preferably made from thick walled tubing 150 with hardened driver points 149. Each slug is long enough to make a completed stack 113 as seen in delivery arm 112 Fig. 24 and allow sufficient stock for the wastage or cutter width of six cuts (cutter 140) and leave a stub of gripping length in the collet 139.

Magazine 138 Fig. 15, is provided with a catch 141 which engages a thumb snap 142 secured to supporting frame 143 which in turn is secured to frame 32. Supporting frame 143 has a clawlike end 144 which serves to widen or expand the otherwise partially closed throat member 145 of said magazine upon its insertion into the device thereby permitting the slugs to move downwardly in response to gravity. This brings the slugs in turn into groove 146, Fig. 34, of slug delivery arm 147, which delivers one slug each cycle to the pin collet 139 (see Fig. 8) at position 148, Fig. 15.

A slug loading driver 151, Fig. 25, pivoted on screw 153 on slug delivery arm 147 and provided with a ball plunger 152, telescoping therein, which is in contact with the slug 137 delivers the slug by torsion of spring 154 into collet 139, Fig. 8. This de-

vice is retracted by roller 155 acting on relatively fixed cam 156, secured on frame 157 which in turn is secured to frame 30.

The slug is gripped in collet 139, Fig. 8, by spring jaws 158 which are caused to grip by the longitudinal movement of closure 159. This closure which is caused to rotate with the collet by wire key 162, is operated by yoke 160 engaging in groove 161, see Fig. 26. Yoke 160 is carried by pivots 163 on arm 164 secured to sleeve 165 journaled on shaft 167. Cam follower 166, also journaled on shaft 167, carries a cam roller 166' which communicates movement to the aforesaid closure 159 from cams 168 and 169, Fig. 9.

Arms 164 and 166 are spring adjusted relative to each other by spring 170 one end of which is rigidly housed in each of the respective arms. This provides a flexible drive for closure 159. The slug 137 is delivered and gripped when pin delivery arm 112 is in its delivering position shown in Fig. 24. Figs. 8 and 15 show the said delivery arm in its receiving position in alignment with the collet. In this position a

measuring spacer rod 171, having longitudinal movement limited by stop 172 which also prevents turning, is caused by a cam 173 on stepped collar 97 Fig. 11 to advance into the pin hole 174 in delivery arm 112 Fig. 8, to an initial position. Then the collet opens and a collet plunger 175 actuated by a spring 176 moves the slug 137 into contact with measuring spacer rod 171 which in turn is pressed tightly against stepped collar 97 which determines the pin lengths. As the stepped collar 97 continues to rotate (see Fig. 1) the measuring spacer under the actuation of spring 176 drops off of each successive step 97' on said stepped collar until mechanism to be described later brings said stepped collar to rest. The collet again grips the slug and a cutter point 180 of cutter 140 slowly rotates into the rapidly rotating slug 137 cutting it off to a predetermined length to match a certain biting of one of the inserted keys 181, Figs. 1, 4, 7, and 11. Again the collet is loosened and the stepped collar advances and the process is repeated six times for each cycle of the cam driver. The stack 113 Fig. 23 is now completed and ready for delivery.

The delivery arm 112 is moved from the receiving position just described to its unloading position (as shown in Fig. 24) by a cam, see Fig. 33 integral with cam ring 182, Fig. 9 acting upon cam follower 183, Fig. 8, through the roller 184. Cam follower 183 is integral with spur shaft 185 pivoted at the tip in plate 186 secured to auxiliary frame 218, secured in turn to base plate 30 while said shaft is pivoted at the bottom in base plate 30. This spur shaft in turn carries a bevel gear sector 187 integral therewith which meshes with bevel gear sector 188,

Fig. 8, pinned to shaft 189 which carries delivery arm 112 rigidly secured thereto. The return of the delivery arm is accomplished by a spring 190, Fig. 15, the upper end of which is secured to the delivery arm 112 and the lower end to frame 32.

Slug delivery arm 147 is not rigidly carried on shaft 189 but is rotatable thereon within limits imposed by stop 191, integral 10 with said slug delivery arm, shown dotted, Fig. 15, which engages with delivery arm 112 directly as shown at one end of its travel and with extended prong 192 thereof at the other end. Slug delivery arm 147 is thus carried only part of the angular (60°) distance described by delivery arm 112 and is limited in such movement by stops 193 and 194, the latter of which is shown dotted.

20 Going back to the collet plunger 175, Fig. 8, there is a collar 195 keyed thereto by rivets 196 which operate in slots 197 in collet 139 to provide for longitudinal movement of the collet plunger 175 together with its collar 195 25 by which it is controlled at certain periods of each cycle by positive cams. A groove 198 in said collar affords a seating for yoke 199 Fig. 13, pinioned in arm 200 integral with shaft 201 journaled in frame 202 bridging between frames 32 and 33. This arm 200 carries a roller 203 operating between cams 205 and 206, Figs. 9 and 13, of cam drum 50. A screw 204 completes the vertical adjustment of shaft 201. This cam action 30 forms a positive knock-out for the gripping stub remaining after the stack of pins is complete and removed and also as a drawback for the collet plunger against the action of spring 176 for the free insertion of a 35 new slug.

Collet closer 159 is journaled in a bearing consisting of two members 207 and 208 forming an oil well 209 having an oil ring 210.

The cutters 140 train and drive is as follows:

An intermittent spur gear 211 Figs. 34, 6, 9 and 16 near the top of the cam drum 50 drives a pinion 212, Figs. 10 and 16, journaled in frame 213 secured to auxiliary 50 frame 42. This pinion carries a spur gear 214 meshing with spur gear 215, Figs. 10 and 16, carried on shaft 216 journaled at the bottom in base plate 30 and near its top in frame plate 217 Figs. 2, 10, 13, and 16. 55 Frame plate 217 bridges auxiliary frames 42 and 218 to which frames it is secured. Shaft 216 carries at its upper extremity a compound helical gear 219 providing two speeds for gear 220 which it drives. Gear 60 220 is carried on shaft 221 to which it is pinned with pin 222 Fig. 16. Shaft 221 has a head 223 provided with a slot 224, engaging with an end spline 225 of shouldered shaft 226 to which a cutter disc arbor 227 65 is secured. This arbor carries cutter 140

and drives same through shear pin 228, Fig. 17.

Cutter 140 is removable from the machine together with its housing consisting of cutter frame 177, front plate 178 and positioning screw 179, for examination of or change of cutters. This is effected by unscrewing positioning screw 179 until dowel point 230 is withdrawn from a dowel hole 231 in frame 32 and then pulling vertically upward 70 on screw 179 with the fore finger and thumb, see Figs. 2 and 8, when the whole unit slides vertically out of T groove 232, provided slot 224 and end spline 225 are in a vertical position, which position they assume at the 75 end of the cycle. Dowels 233 Fig. 17 are used for positioning the front plate 178 on the cutter frame 177. Shaft 226 has a projection 234 which forms a bearing in front plate 178. Cutter 140 has two blades 180 80 and the gear ratio between cutter 140 and cam drum 50 is such as to cause the cutter to make three complete revolutions to each revolution of the cam drum thus making six 85 cuts to each cycle.

There is a hole 235, Fig. 15, through front plate 178 the position and size of which is shown by dotted line Fig. 17, thru which a pointed instrument may be inserted to engage holes 236 in cutter 140 for the purpose 90 of manually backing cutter 140 out of a partly severed slug should shear pin 228 fail during the process of cutting. Peripheral portions of cutter 140 bounded by dotted line 237 are thinned down as shown at 95 238 so that the intervening distance between the pin segment just formed and the remaining portion of the slug which has been advanced by plunger 175 under tension of spring 176, Fig. 8, is less than the thinnest 100 possible pin segment, that is, a segment of initial length, .0125 of an inch in length in this instance, so that such a pin could not leave the stack and escape through the cutter space into the waste chute 239 whence the 105 waste passes through hole 240 shown dotted, and out of the machine at the bottom.

A cutting and burnishing burring tool 241 the rear end of which is shown in Fig. 6 and in cross section, Fig. 9, operates horizontally and transversely of the machine, guided in frame 32. The forward end of said tool is guided in groove 242, Fig. 17, of the cutter housing 177 and a similar and opposite groove not shown, on the inside of 115 the front plate 178. This tool forms a slight 120 curve or chamfer on the adjoining corners of the segments being severed.

It is actuated through lever 244 of bell crank 243 Figs. 6, 9, 13, and 30, by spring 125 247 Figs. 6 and 30, secured thereto the opposite end of which is secured to stud 248 of frame 249 secured to base plate 30. This tool 241 is retracted through cam follower 245 operating on cam 246 of cam drum 50. 130

and is provided with roller 293 mounted in lug 294 that engages spring mandrel control cam 295 of cam drum 50. Lever arm 289 is yieldingly held in contact with cam 295 by flat spring 296, Fig. 6, which serves to withdraw mandrel 282 by the exertion of a resilient force after the spring has been wound and delivered to spring delivery arm 115 and cam 295 releases lever arm 289. Fig. 33 shows a diagram of cam 295 in which the uniform slope 20° to 195° represents the forward movement of the mandrel in winding the open coils of the spring, the abrupt raise immediately following 195° represents a period in which the mandrel is moved forward slightly while making, preferably two complete revolutions to wind two closed coils on the end of the spring the interval between the abrupt raise 195° and 270° represents forward movement of mandrel to cut off spring by shoulder 284 and deliver spring to spring delivery arm 115, the interval between 270° and 300° represents release of cam lever 289 by cam 295 and retraction of mandrel and the remaining interval represent period of rest before next operation. After spring is wound, cut off and delivered into arm 115 it will expand enough so that the end of the spring will engage block 280 and prevent the spring from being withdrawn with the mandrel.

Spring delivery arm 115 is loosely mounted on shaft 189, Fig. 8, and is adapted to be moved from the spring receiving position, Fig. 10, to the spring delivery position Fig. 24, when shaft 189 is oscillated, Fig. 13, by engagement of a pin 297 on the spring delivery arm with the opposite ends of a slot 298 in a gear sector 299 that is secured to shaft 189, Fig. 29.

The caps 118 which serve as stoppers to hold the tumbler pins and springs in the lock cores are stored in a removable magazine 300, Figs. 34, 2 and 13, having a longitudinal cap receiving chamber or bore 301 of circular cross sectional shape open on the front side to afford a slot through which access may be had to said bore 301. The magazine 300 is arranged to be supported in suitable recesses 302 and 303 formed in the respective frame members 42 and 218, Figs. 2 and 13, with one end against the cap delivery plate 117. The caps 118 are fed toward the cap delivery plate 117 as used by a follower 304, Figs. 2 and 12, that protrudes into bore 301. The follower 304 is secured to a rod 305 that is guided for movement in a guide 306 on the door 262 and is urged toward the head end of the machine by a spring 307. The rod 305 is arranged to project outwardly through a suitable perforation in a flange 308 on the edge of door 262 for purposes hereinafter explained and is provided with a stop 309, Fig. 12, arranged to strike the flange 308 to arrest the move-

ment of said rod in the position in which the last cap in the magazine 300 is delivered to the cap delivery plate 117.

The cap delivery plate 117 Fig. 29 is of substantially semicircular shape, is just thick enough for the reception of a single cap 118 and is provided with a suitable perforation which, at the proper intervals in the cycle of operation of the machine, is aligned with the cap magazine 300 and the loading plunger 119, respectively. The cap delivery plate 117 is mounted on frame piece 218 by pivot 310, is peripherally guided for oscillation and to prevent the escape of the cap 118 by guide member 311 and is oscillated by integral gear teeth 312 on cap delivery plate that mesh with gear teeth of idler gear 313 which in turn meshes with gear segment 299 on shaft 189, Figs. 13 and 29.

Certain automatic stop and safety devices are as follows:

The friction drive associated with cam cylinder 55 makes possible the stopping of said cam cylinder at the end of any cycle by engagement of locking plunger 59 with toothed ring 60 on cam cylinder 55, Figs. 9 and 27, as previously explained. Said locking plunger is arranged to be released manually and to be operated or set by four different automatic stop devices as follows: first, by devices that operate when all of the pin slugs are exhausted; second, by devices that operate when the spring wire is exhausted or broken; third, by devices that operate when all of the caps in the cap magazine are exhausted and fourth, by devices that operate after all of the barrels of a lock have been filled and the key carriage is moved to its outermost position. In all of the operations above mentioned the locking plunger 59 is moved by a lever arm 314 on a transverse rocker shaft 315 that is mounted for oscillation in upright frame brackets 316 and 317 that are secured to the base frame 30, Figs. 1, 2, 5 and 9. The pin slug stop mechanism comprises an upright lever arm 318 arranged to press against the outer end of a rod 319, Figs. 6 and 30 that is guided for longitudinal movement in a tube 320 that is secured to end frame member 32. The inner end of the rod 319 is secured to a bracket 321 having a plunger 322 that projects through a hole 323, Fig. 25, in the frame plate 32 directly in alignment with the position that will be occupied by the last pin slug 137 from the magazine 138 just before it drops into groove 146 of slug delivery arm 147. A spring 324, Figs. 6 and 30, serves to press the bracket, 321 outwardly away from the plate 32 thereby ordinarily keeping plunger 322 retracted so that it will not interfere with pin slugs 137. Bracket 321 is provided with slidably connected pin 325 yield-

At the end of each cycle said tool is retracted sufficiently to allow the removal of the cutter housing unit. Bell crank 243 is mounted on shaft 167 Fig. 26 on which it is free to turn.

The making and delivery of the spring is as follows:

- Wire 250 Fig. 12 for making the springs is wound on a spool 251 mounted on stud 252. This spool is held on the stud 252 and frictionally gripped against easy turning by balls 253 and spring 254 (shown dotted) the hole 255 in which these operate is buried over at the surface 256 of stud 252 to prevent the removal of balls 253 and spring 254 when the spool 251 is removed. Balls 253 fit into a slight internal annular groove (not shown) in the hub 257 of spool 251 to provide alignment of spool on stud 252, as the spool turns in response to the wire being drawn forward (to the right, Fig. 12) by the wire advancing device 258, the operation of which is shown more fully in Fig. 22. The wire is manually fed through holes 259 and 260 of base block 261 of door 262 hinged at 263 to hinge supports 264 secured to base plate 30 by screws 265 Fig. 12. This door is shown open in Fig. 2. The wire is also manually fed into wire feed plunger 266 which is adjusted to longitudinal movement on stud 267 of base block 261 and in hole 268 of block 269 which in turn is secured to base block 261. This plunger 266 has a pivoted pawl 270 which grips the wire and thereby automatically feeds it forward with foot 271 when actuating member 272, to be described later, comes in contact therewith and moves the wire feed plunger 266 in the direction in which the wire 250 is to be advanced. When the wire feed plunger is moved in the opposite direction (to the left Figs. 12 and 22) the wire will slide freely through said wire feed plunger and pawl foot 271 will take a new grip on the wire. Actuating member 272 for moving wire feed plunger 266 is secured to a block 273, Fig. 31 that is guided for reciprocatory movement lengthwise of the machine on a horizontal guide rod 274 that is supported at its respective ends in frame members 33 and 218. Block 273 is further guided by the walls of frame member 42 to prevent said block from turning on guide rod 274. Block 273 is arranged to be moved to the left, Fig. 2, by lever arm 120 operating through slot in frame 33 striking against the end of a rod 275 that is rigid with the block 273 and to be moved to the right by compression spring 276 on guide rod 274 between frame member 218 and the end of block 273. Only a small portion of the movement of the lever 120 is utilized in moving the wire feed plunger and the wire feed plunger is moved forward on each forward excursion of the loading plunger.

Upon leaving the wire feed plunger 266 the wire 250 passes into and through a wire conduit tube 277 which extends upwardly along the door 262 and is secured near its upper end to a supporting bracket 278 that is rigid with and protrudes inwardly from the upper edge of the door, see Figs. 2, 12 and 29, and that serves, when the door 262 is closed to hold the wire exit end of the tube 277 in close proximity to a wire inlet perforation 279 in a wire holding member 280 that is rigidly secured to frame member 218 and is provided with a longitudinal perforation 281, Figs. 10 and 29.

Axially aligned with the perforation 281 in member 280 is a spring winding mandrel 282, Figs. 10 and 34, having a diametrically arranged slot 283 in its forward end which, at a predetermined time, is brought to rest within the wire holding member 280 in alignment with the wire inlet perforation 279 so that when the wire 250 is advanced by movement of the wire feed plunger 266 the end of such wire, previously positioned in perforation 279, Fig. 29, will be caused to enter slot 283, after which the mandrel 282 will be rotated and advanced simultaneously by mechanism hereinafter explained, to first wind a desired number of open coils; then one or more closed coils; then to cut off the spring, discharge the same into the spring deliver member or guide 115 and withdraw the mandrel 282 into the position of rest shown in Fig. 10. When the spring begins to wind the end of the spring wire held within the slot 283 in the forward end of the mandrel 282 will be bent sharply in an obvious manner so that it will occupy a substantially diametrical position across the end of the spring and will, when assembled, bear against the end of the last tumbler pin of a stack. The mandrel 282, Fig. 10, is provided with a spring cut off shoulder 284, a shifter collar 285 and has an integral rear end portion of larger diameter that is splined for longitudinal movement in a sleeve 286. The sleeve 286 is journaled in bearing brackets 287 suspended from fixed plate 217 and is driven from the shaft of pinion 212 by bevel gears 288, Fig. 10. As previously explained pinion 212 meshes with, and is driven by, intermittent spur gear 211 on the upper end of the cam drum 50, said intermittent gear being without teeth around a portion of its circumference so that the pinion 212 may have a period of rest while the spur gear 211 continues to rotate.

The mandrel 282 is moved longitudinally by cam operated lever arm 289 Figs. 10 and 26, having upwardly protruding end 290 carrying yoke 291 that engages mandrel shifter collar 285.

Lever arm 289 is pivotally mounted, by means of bracket 292, on shaft 167, Fig. 26,

ingly supported by compression spring 326, arranged to be engaged by cam foot 327 on sleeve 243 carrying cam follower 245 that operates on cam 246. At intervals during each cycle of operation cam foot 327, actuated from cam 246 will exert a pressure on the end of pin 325, which pressure, if plunger 322 abuts against the end of a pin slug 137, will cause pin 325 to move in bracket 321 and compress spring 326 without moving bracket 321. If however the last pin slug 137 has dropped into the slug delivery arm, or the pin slugs have failed to feed down properly so that there is no pin slug in alignment with the plunger 322 then when cam foot 327 operates on pin 325, spring 326, which is stronger than spring 324, will move bracket 321 toward frame plate 32 and by moving rod 319 and lever arm 318 will oscillate rocker shaft 315 and move locking plunger 59 into locked engagement with ring 60 on cam drum 50 thereby stopping the machine.

Rocker shaft 315 is provided near the right end Figs. 5 and 8 with an upright lever 328 that is pivotally connected with an operating bar 329 having a push button 330 by which it may be manipulated manually either to move locking plunger 59 into a locked position or to release or withdraw said locking plunger after it has been moved into a locked position by any of the automatic stop devices. Operating bar 329 has guide pins 331 on its forward end that fit slidably into suitable perforations in frame member 32 and further has rigid foot portion 332 that projects downwardly and to the right, Fig. 5, and is arranged to be engaged by the end of the cap follower rod 305 after the last cap has been used and by spring wire control plunger 333 slidably in block 334 on door 262. Plunger 333 is urged toward foot portion 332 by spring 335 shown dotted in Fig. 12, and is connected at its inner end with the upper end of lever arm 336 that is fulcrumed at 337 and has its lower end pivotally connected with short end of lever arm 338, Fig. 12. Lever arm 338 is fulcrumed at 339 and has on its outer end a catch 340 bent at right angles thereto and arranged to be positioned within a slot 341 in the wire guide base block 261 below wire 250 so that it will ordinarily be held down by wire 250 but will be released when the wire is all used up thus permitting lever arm 338 to move upwardly and permitting plunger 333 to move operating bar 329 and lock cam drum 50.

From the preceding description it will be seen that when the caps are all used up cap follower rod 305 will engage operating bar 329 and lock the machine and when the spring wire is all used up plunger 333

will operate in a similar manner to lock 65 the machine.

Operating and release bar 329 is further provided with a lug 342 arranged to be engaged by a cam 343 that is secured to the key carriage 345 Fig. 4 and that operates 70 to move bar 329 and lock cam drum 50 when all of the barrels of a lock core are filled.

The key carriage is made up of two relatively movable parts namely an inner key 75 carriage member designated generally by the numeral 344 and an outer key carriage member or key holding device, Fig. 21, designated generally by the numeral 345. The inner carriage member is supported for 80 movement toward and away from the escapement drum 84 by roller 346, Figs. 7 and 8, on opposite ends thereof that rest on suitable supports, not shown, on the end frame members 32 and 33, and by a rigid arm 347 85 slidably in a bracket 348 on the frame member 202, Figs. 4 and 13. Stop members 349 and 350 are provided on the arm 347 on both sides of the bracket 348 to limit the movement of the inner carriage member in both 90 directions. The edge of inner key carriage member 344 adjacent escapement drum 84 is shaped to conform to the peripheral contour of said escapement drum and is provided with three longitudinal slots 351 arranged one above another and through which the ends 352 of lever arms 353 project, Figs. 11 and 13 said ends being arranged so that, at the proper time they will engage with certain outwardly protruding pins 354, Fig. 100 105 11 on the escapement drum 84 and stop the rotation of said escapement drum thereby determining the length of a lock tumbler pin that is to be cut off. The lever arms 353, Figs. 3, 4, 11, 18 and 19, are provided with enlarged outer ends 355 that are disposed within slots 356 in the rear portion of the carriage member 344 and are fulcrumed on pivots 357, said enlarged ends 355, being 110 slotted as at 358 Fig. 11, and provided with adjustment screws 359 by which the positions of the pin engaging ends 352 of such lever arms may be adjusted. Springs 360 serve to urge the levers 353 to the right as seen in Fig. 11. The enlarged ends 355 of the lever arms 353 have integral pawls 361 arranged to engage blocks 362 on positioning members, 363 Figs. 18 and 19 that are 115 120 125 slideable in guideways 364 in the outermost side of carriage member 344 and that have key engaging pins 365, Fig. 11 on their forward ends arranged to fit within notches 366 in the edges of keys 181 held in key supports 368 of key holder 345 and arranged to project into guideways 369 in the carriage member 344.

The positioning members 363 are provided with pins 370 that project outwardly into

perforations in a plate 371 that is slidably mounted on the outer side of the key carriage member 344, Figs. 11, 18 and 19, plate 371 is arranged to be moved, Figs. 1, 3, 4 and 11, by a lever arm 372 fulcrumed at 373 and having its outer end connected with a lug 374 on the plate 371 and its inner end connected by means of slot 375 and pin 376 with operating bar 377 that is pivotally connected with lever 378, Figs. 2, 3, 4, and 32. Springs 360 acting through levers 353 and positioning members 363 yieldingly urge plate 371 to the left thereby tending to hold lever 372 in the position shown in Fig. 3. 15 When lever 378 moves to the left, Figs. 3 and 4, lever 372 will be moved therewith and caused to move plate 371 to the right and withdraw pins 365 from engagement with the keys 181. After a complete set of pins 20 have been cut and delivered into a lock cylinder the carriage member 344 will be moved rearwardly more than the usual amount by the cam that controls the same, as herein after described and the rear end of the lever 25 372 will be moved to the left far enough to permit a spring pressed catch 379 to drop behind the end of lever 372 and hold said lever 372 in a position in which the pins 365 are withdrawn from the notches in the keys 30 181 while said keys are being withdrawn a distance equal to one notch from the inner key carriage member 344 by escapement means hereinafter described. During this operation the lost motion afforded by slot 35 375 and pin 376 permit lever 378 to move to the right. As carriage member 344 returned toward escapement drum 84 the end of lever 40 372 will drop off of catch 379 and said catch will then be inoperative until near the end of the next succeeding cycle of movements.

The lever 378 which is of bell crank shape is urged to the right, Figs. 3 and 4, by a tension spring 380 and is arranged to be moved to the left by the action of a pin 45 381 on the lever that projects into a perforation in a lug 382 Figs. 2, 4 and 13, on the rigid frame bracket 202. A screw 383 in the lug 382 makes it possible to adjust the oscillating movement that will be imparted to the lever 378 by a given rearward movement of inner key carriage member 344.

Inner key carriage member 344 is arranged to be moved rearwardly by a rigid arm 384 on shaft 167, Figs. 4, 13 and 26, that engages with a shoulder 385 on arm 55 347 of key carriage. Shaft 167 is operated by cam follower 386, Figs. 9, 13 and 26, that engages cam 387 on cam drum 50. Spring 388 connecting key carriage bracket 60 347 with frame bracket 348 yieldingly urges the carriage 344 toward escapement drum 84. Cam 387, Fig. 33, is arranged to impart a plurality, preferably six, successive movements of equal amplitude to carriage 65 member 344, each time moving the same

away from escapement drum 84 and releasing the previously engaged lever 353 and pin 354 so that said escapement drum may advance until stopped by the lever 353 next in line with a pin 354 on said escapement 70 drum as the carriage 344 moves rearwardly a stop 439 on the end of said carriage will be brought into alignment with one of a plurality of teeth 440, Fig. 20 on a disc 441 on the end of the escapement drum 84 75 so that when the escapement drum is released by a lever 353 it will only move far enough to clear the end of that lever and the previously engaged pin and will then be held by teeth 440 and stop 439 until the 80 carriage again moves back toward the escapement drum, whereupon stop 439 will release teeth 440 and escapement drum 84 will be free to rotate until stopped by the lever 353 next in line with a pin 354. Teeth 85 440 are arranged, with respect to pins 354 that one of the teeth 440 will always be in a position to engage stop 439 the instant a pin 354 has cleared the end of a lever 353 with which it was previously engaged. Two teeth 442 of larger dimensions than the teeth 440 are provided to take care of greater movement of the carriage member 344 which occurs near the end of each cycle. By operating in the manner above described 90 the teeth 440 and stop 439 keep the escapement drum in proper sequence and made it impossible for the drum to move any of the pins 354 past the levers 353 with which they should engage while the levers are withdrawn. 100

After a stack of pins are measured and cut off and while said stack is being delivered to a lock the cam 387 operates to move the key carriage a greater distance 105 than usual away from escapement drum 84 thereby imparting more than the usual amount of movement to lever 378 and causing escapement teeth 388 on the upper side of lever 378 to release one only of a plurality of escapement teeth 389 on rod 390 of key holder 345, Figs. 5, 8, 13 and 32, thereby permitting tension spring 391, which is connected with rear edge of carriage member 344 and with forwardly protruding arm 392 of key holder 345, to move said key holder rearwardly far enough to bring the next succeeding notches in the respective keys 181 into alignment with pins 365 on positioning members 363, said pins 110 365 being held out of engagement with the keys by lever 372 and catch 379 as hereinbefore explained while key holding member is being moved relative to key carriage member 344. As many escapement teeth 389 115 may be provided on the rod 390 as are necessary to afford the number of rearward movements desired to complete the filling of a lock core. 120

Two positioning members 363 with pins 130

365 operating in two successive key notches are provided, Fig. 11, in connection with the middle key as hereinafter described. Swinging movement of the lever 387 sideways is limited by a screw 393 that projects through a slot 394 in the lever and is rigidly secured to the carriage arm 347, Figs. 4 and 13.

Escapement teeth 388 on lever 378 may be entirely disengaged from teeth 389 on bar 390 to permit key holding member 345 to be moved inwardly with respect to carriage member 344 by exerting a downward pressure on a suitable finger piece provided on the outer end of said lever 378 and depressing the same.

Safety devices to prevent depression of the lever arm 378 except when the machine is stopped are provided as follows: A perforation 395 in said lever arm, Figs. 13 and 32, is arranged to register with a pin 396 on a plate 397 when the plate is in a certain position that is determined by the position of the locking plunger 59, Figs. 9 and 27. The plate 397 has a slot 398 in its outer end that fits over and is guided on the screw 393 and such plate is pivotally connected at the other end with an arm 399 that is rigidly secured to the top end of a rod 400, Figs. 4, 9, 13 and 27, pivoted at the upper end in a bracket 401, thence extending downwardly and pivoted at its bottom end in a rigid frame block 402, the rod 400 being curved as shown in Fig. 27 to clear the escapement drum shaft 85. A rigid bell crank arm 403 on the bottom end of the rod 400 has a stud pin 404 on its outer end that projects downwardly into a longitudinal slot 405 in a plate 406 that is secured by a pivot 407 to the upper side of the locking plunger 59, Figs. 9 and 27. The plate 406 has one edge that overhangs the edge of locking plunger 59 to form a ring engaging member 408 that is adapted to be engaged by a tooth on the lock ring 60 to move plate 407 when locking plunger 59 is moved inwardly. A spring 409 connected with bell crank arm 399 at the top of the machine and acting through rod 400 and lower bell crank arm 403 serves to hold side member 408 of plate 406 away from locking plunger 59 when said locking plunger is withdrawn from toothed ring 60 and thus serves to hold pin 396 out of registration with perforation 395 so that lever 378 can not be depressed. When locking plunger 59 is moved into engagement with toothed ring 60 the tooth on said ring will strike against ring engaging member 408 and move the same until it strikes against the side of the locking plunger thus acting through lower bell crank 403, rod 400, upper bell crank 399 and plate 397 to move pin 396 into registration with perforation 395 so that lever 378 may be depressed. This alignment of pin 396 and perforation 395 will occur at the end of a cycle of operation of the machine.

The key holder 345 is movably supported relative to the carriage member 344 by the key supports 368 which fit slidably in the guideways 369 Figs. 8 and 11 and by smaller rollers 410, Figs. 8, 18 and 19 and larger flanged side rollers 411, Figs. 4, 6 and 8 all of which engage with a U shaped frame portion 412 that is a fixed part of the key holder 345 and is positioned above the carriage member 344 when assembled. Rod 390 which fits slidably within a suitable perforation in a lug 413 on bracket 347 of carriage member 344 also serves as a further guide and support for key holder 345. Key holder 345 is provided with an outer plate 414 to which the key supports 368 are rigidly secured, said plate having on its outer surface a plurality of grooves and recesses Fig. 21, of peculiar shape more specifically hereinafter described that are arranged for the reception of three key locking members 415, 416 and 417 that are urged toward the left by springs 418 and that have relatively narrow flanges or locking blades 419 arranged to enter suitable notches 420 in keys 181 in any one of four different keyways 421, 422, 423 and 424. A cover plate 414' serves to retain the key locking members 415, 416, and 417 in the grooves on the front of plate 414. The key locking members 415, 416 and 417 have relatively thin forwardly extending ends, Fig. 21, that are each provided with two equidistantly spaced perforations 425 and 426 and the medial one 416 of which is provided with a third perforation 427. When the locking members 415, 416, and 417 are all at the limit of their movement in either direction the three perforations 425 will be in vertical alignment and the three perforations 426 will also be in vertical alignment. The frame plate 414 is provided in the bottoms of the grooves that carry the locking members 415, 416 and 417 with perforations 428, wherein pins 429 are slidably disposed said pins being secured to three separate cross bars 430, 431 and 432 respectively that are pivotally connected with oppositely disposed yoke members 433, Figs. 11 and 28, which are pivotally secured to the ends of parallel spaced apart bell crank arms 434 that are secured to shaft 435 which is mounted for oscillation on arm 436 that is rigidly secured to the end of the key holding carriage. Shaft 435 is connected by lever 437 and link 438 with a rigid stud 367 on operating bar 329 Figs. 1, 5 and 28 so that when the locking plunger 59 is in a locked position the cross bars 430, 431 and 432 will all be retracted and will withdraw all of the pins 429 from engagement within the perforations in the ends of the key locking members 415, 416 and 417 and when the

locking plunger 59 is in an unlocked position the yoke bars 430, 431 and 432 will be moved outwardly and the pins 429 will be thrust into certain perforations in the key 5 locking members 415, 416 and 417 thus locking said key locking members against movement when the cam drum 50 is free to rotate. This constitutes a safety device that makes it impossible to move the keys when the machine is running or to start the machine 10 until certain keyways have been filled.

It will be seen that the yoke as a whole may assume an inclined position with the pins on the medial bar 431 and on either one 15 of the outside bars 430 or 432 entering the perforations in the key locking members 415, 416 and 417. By operation in this way the yoke mechanism including yoke bars 430, 431 and 432 may be caused to lock the key 20 locking members 415, 416, and 417 when keys are inserted in all keyways 421, 422, 423 and 424 or when only one key is inserted in the centrally disposed keyway 423, or when the central keyway and any one or two 25 of the other keyways are filled, or when two keyways at opposite ends or the three keyways at opposite ends are filled and the other keyways are empty. When all keyways are filled all perforations 425, 426 and 30 427 will be moved into registration with their respective pins thus allowing all bars of the above mentioned yoke to be moved forwardly. If only the central keyway is filled perforations 425 on upper and lower 35 key locking members 415 and 417 and perforation 426 on middle key locking member 416 will be in alignment with pins 429 on middle yoke bar 431 and perforation 427 on middle key locking member 416 will be in 40 alignment with pin 429 on yoke bar 432 thus permitting the yoke member to assume an inclined position as the pins on the yoke bars 431 and 432 enter the perforations in the key locking members 415, 416 and 417 45 and lock said key locking members while the pins on the yoke bar 430 abut against the key locking members 415 and 417 at places where there are no perforations. In a similar manner if the single perforation 50 427 in the extreme end of the medial key locking member 416 is moved out of registration with the pin 429 on the yoke bar 432 then the perforations 425 in both the upper and lower key locking members 415 and 417 55 must be moved into registration with pins 429 on yoke bar 430 before the yoke can be moved forwardly to permit the cam drum 50 to be released by the locking plunger 59.

The grooves in which the key locking members 415, 416 and 417 operate are so shaped as to form stops that limit the movement of said key locking members in both directions. Springs, 418 are provided for 60 yieldingly urging the key locking members 65 into locked engagement with the keys and a

thumb piece 443 pivoted on the bracket 436 near the ends of the key holding members is provided for moving the key holding members to the right to permit the insertion or removal of keys.

Arm 436 on the end of key holding member 345 extends downwardly and engages with core carriage, 110 will be moved simultaneously with key holding member 345. Suitable means, not shown are provided for 75 centering a lock core 111 in the key carriage 110 and for securing the same in the proper position therewith during the operation of filling said lock core.

Fig. 34, is a schematic lay-out showing as 80 fully and completely as possible the relative positions of the several parts, the different driving connections, and the center lines of the various operating units.

One operation that this machine is intended to perform is the setting up or filling 85 of a pin tumbler lock to two shear lines to fit a single control key so that when the control key is thrust into the lock as far as it will go it will position the pins so that they will register with respect to one shear line and when the control key is withdrawn one notch it will position the pins so that they will lock on the first shear line but will register with respect to a second shear line. 90 Other operations include the setting up of a lock to a single shear line to fit two, three or four different keys or the setting up of a lock to two shear lines so that from one to four different keys will operate the lock on one shear line and one of said keys termed the control key will also operate the lock on the second shear line.

In setting up a lock a lock core 111 is inserted in the core carriage 110, the keys 181 105 that the lock is to be set up to fit are inserted in the various keyways, the motor is started and the cam drum 50 is released by pressing inwardly on button 330 of release member 329 thus starting the operation of the machine. As the escapement drum rotates the pins 354 will successively engage with the ends of the levers 353, the positions of which are determined by the depth of the notches in the keys 181, and stop the drum. 110 Each time the drum is stopped a tumbler pin of the proper length to register with the shear line of the lock when fitted with the determining key or a duplicate thereof is cut off as hereinbefore explained and delivered to pin delivery arm 112. As soon as this operation has taken place the escapement drum 84 is released and moves around until it is stopped by another lever 353 positioned by another key whereupon another tumbler pin is measured and cut off so that the combined length of the last cut and all 115 previously cut tumbler pins will be such as to cause the end of the last cut tumbler pin to line up on the shear line of the lock 120 125 130

when fitted with the key that determined the length of the last cut tumbler pin. In this way the keys will operate successively to determine the lengths of the tumbler pins for a barrel of the lock the key with the most shallow notch determining the length of the first tumbler pin in the stack and keys with successively deeper notches determining the length of successive tumbler pins until the stack is complete. After a stack of pins are cut and delivered to the pin delivery arm 112 they are moved, together with a spring and cap into alignment and are loaded into a barrel of a lock core 111 as previously explained. After the last pin has been measured the pin drum escapement cam will operate to release engagement of escapement teeth 388 and 389 thereby permitting key holder 345 to move keys 181 rearwardly one notch preparatory to cutting a stack of keys for filling the next barrel of the lock.

The number of tumbler pins in a stack will be determined by the number of keys that the lock is being set up to fit.

In setting up locks to operate on two different shear lines different levers 353 are adjusted so that the same key notch will cause them to assume different positions thereby measuring tumbler pins of different length. For instance one key, as the middle key 181 shown in Fig. 11 may be engaged by two positioning members 363 operating in successive notches, and connected with different levers 353, the preceding one of which may be adjusted so as to always measure a longer pin than the other for the same notch of a key thereby setting up a lock in which all of the pins will line up on one shear line while the second positioning mechanism sets up the same lock at the same time to operate on a different shear line. In this way it is possible to set up a lock to operate on one shear line when a key is thrust entirely into said lock and to operate on another shear line when said key is withdrawn one notch. When keys are made to operate in this manner it is necessary to form a bevel on the end of the key that will act as an additional key notch in setting up the lock and that will receive the end stack of tumbler pins and cause them to line up on the proper shear line in operating the lock.

The foregoing description and accompanying drawings disclose one operative embodiment of my invention but it will be understood that this disclosure is merely illustrative and that such changes may be resorted to as are within the scope and spirit of the following claims.

I claim:

1. In a lock filling machine, devices for cutting off tumbler pins and means governed by the shape of a key for automatically

determining the lengths of said tumbler pins.

2. In a lock filling machine, devices for cutting off tumbler pins and means arranged to be actuated by serrations on the edges of keys for determining the lengths to which said tumbler pins are cut.

3. A lock filling machine embodying devices for cutting off tumbler pins, means governed by the shape of keys for automatically determining the lengths of said tumbler pins and means for automatically loading said tumbler pins into a lock.

4. In a lock filling machine, devices for cutting off tumbler pins for a lock, means governed by the dimensions of serrations in keys that are to fit said locks for determining the lengths to which said tumbler pins are to be cut and means for loading said tumbler pins into a lock.

5. In a lock filling machine, devices for cutting off tumbler pins to form a stack, means governed by serrated keys for determining the length of each tumbler pin in proportion to a serration of different dimension on said keys and means for loading said stack of tumbler pins into a lock.

6. A machine for filling a lock to match a plurality of keys of different combinations embodying pin cut off means, pin measuring means governed by a plurality of different keys for determining the lengths to which the pins are to be cut in proportion to the dimensions of notches in said keys and means for automatically loading cut off pins into a lock.

7. In a lock filling machine, devices for cutting off tumbler pins, a key carriage, arranged to have keys inserted therein, means governed by the shape of the keys in said key carriage for determining the lengths to which the pins are cut off and means for loading said pins into a lock.

8. In a lock filling machine, devices for cutting off tumbler pins, a key carriage arranged to receive a plurality of keys, pin measuring means for determining the lengths of the pins to be cut, devices arranged to engage with the keys in said key carriage for positioning said pin measuring means and automatic means for loading the cut off pins into a lock.

9. Pin cutting and stack forming means embodying pin cut off devices, a key carriage arranged to receive a plurality of keys, pin measuring means for determining the lengths to which the pins are cut and devices arranged to engage with the keys in said key carriage for controlling the position of said pin measuring means.

10. In a lock filling machine, a key holding device, positioning means arranged to engage with keys that may be inserted in said key holding device, pin measuring devices arranged to be positioned by said posi-

- tioning means, means for cutting off pins of lengths determined by said pin measuring devices to form stacks and means for loading said stacks of pins into a lock.
11. In a lock filling machine, a key holding device arranged to have keys inserted therein, positioning means arranged to engage said keys, devices for adjusting the relative positions of said keys and said positioning means, pin measuring devices arranged to be positioned by said positioning means, means for cutting off pins of lengths determined by said pin measuring devices and means for loading said cut off pins into a lock.
12. A lock filling machine embodying means for holding and advancing pin slugs, means for cutting off said pin slugs, a key holding device arranged to have keys inserted therein, means governed by the shape of said keys for determining the length of the pins that are cut from said pin slugs and means for loading said cut off pins into a lock.
13. A lock filling machine embodying pin slug feeding means, pin slug holding means for receiving the slugs singly from said slug feeding means, measuring devices for determining the position of a slug in said slug holding means, a key holding device arranged to receive keys, means engaging said keys for controlling the operation of said measuring devices, devices for cutting off slugs that are held in said slug holding means to form stacks of pins and means for loading said stacks of pins into a lock.
14. A lock filling machine embodying pin slug holding means, measuring devices for positioning a pin slug in said holding means, a key holder arranged to receive keys, means arranged to engage said keys and operative on said measuring devices to determine the position of a pin slug in said holding means, devices for cutting off said pin slugs to form stacks of tumbler pins and means for loading said stacks of pins into a lock.
15. In a lock filling machine, pin measuring and cut off devices embodying means for holding and rotating a pin slug, a cutter for cutting off tumbler pins from the rotating pin slug and means governed by the shape of keys for automatically determining the length to which said tumbler pins are cut.
16. In an automatic lock filling machine, a collet for holding a pin slug, means for rotating said collet, pin measuring devices for determining the position of a pin slug in said collet, a key holder, positioning means operated by keys in said key holder for governing said pin measuring devices, a cutter for cutting off tumbler pins from said pin slug, means for receiving said cut off tumbler pins to form a stack and means for loading said stack into a lock.
17. An automatic lock filling machine embodying a rotatable collet for holding pin slugs, pin measuring devices for determining the position of a pin slug in said collet, a key holding carriage, positioning means operated by keys in said carriage for governing said pin measuring devices, means for moving the keys relative to the positioning means, a cutter for cutting off tumbler pins from said pin slugs to form stacks and means for loading said stacks of tumbler pins into locks.
18. An automatic lock filling machine embodying devices for cutting off tumbler pins, means for receiving said tumbler pins to form stacks, spring supply means and devices for loading said stacks of pins and springs into locks.
19. In an automatic lock filling machine, devices for cutting off lock tumbler pins, means for receiving said pins in the form of stacks, spring supply means, cap supply means and devices for loading said tumbler pin stacks and said springs and said caps into locks.
20. In an automatic lock filling machine, devices for cutting off tumbler pins means for receiving said tumbler pins in the form of stacks, means for winding and cutting off springs and devices for loading said stacks of pins and said springs into locks.
21. In an automatic lock filling machine, means for measuring and cutting off tumbler pins, means for receiving said tumbler pins in the form of stacks, means for winding and cutting off springs, cap supply means and means for loading said stacks of pins, said springs and said caps into locks.
22. An automatic lock filling machine embodying means for supplying stacks of tumbler pins cut to conform to a predetermined lock combination, spring supply means, cap supply means and means for loading said stacks of tumbler pins, said springs and said caps into a lock.
23. An automatic lock filling machine embodying means for supplying stacks of tumbler pins cut to conform to a predetermined lock combination, means for winding and cutting off springs, cap supply means and devices for loading said stacks of tumbler pins, said springs and said caps into locks.
24. An automatic lock filling machine embodying means for supplying stacks of tumbler pins cut to conform to a predetermined lock combination, spring supply means, cap supply means, lock core holding devices, ejector means for clearing the pin receiving holes in lock cores and loading means for loading the stacks of pins, the springs and the caps into lock cores.
25. In an automatic lock filling machine, a core holding device arranged to receive a lock core, ejector means for clearing the pin receiving holes in said lock core, means for cutting stacks of tumbler pins to conform to a predetermined lock combination,

means for delivering said stacks of tumbler pins into a position in alignment with a pin receiving hole in said lock core and means for loading said stacks of pins into said lock core.

26. In an automatic lock filling machine, a core holding device arranged to receive a lock core, an ejector for clearing the pin receiving holes in said lock core means for cutting stacks of tumbler pins to conform to a predetermined lock combination, means for delivering said stacks of tumbler pins into a position in alignment with a pin receiving hole in said lock core, spring supply means, means for delivering springs into a position in alignment with said hole in said lock core, cap supply means, means for delivering said caps into a position in alignment with said hole in said lock core and loading means for loading said stacks of tumbler pins, said springs and said caps into said hole in said lock core.

27. In an automatic lock filling machine, pin slug supply means, means for receiving and cutting up said pin slugs and automatic safety devices for stopping said machine when no pin slugs are available for delivery to said pin slug receiving means.

28. In an automatic lock filling machine spring winding devices, means for supplying wire to said spring winding devices and automatic safety mechanism arranged to be released by the absence of wire in parts of said machine for stopping said machine if the supply of wire is exhausted.

29. In an automatic lock filling machine, cap supply devices including a spring pressed cap follower and automatic safety means governed by said cap follower for stopping said machine if the supply of caps is exhausted.

30. In an automatic lock filling machine, a device for holding a lock core, means for filling tumbler pin receiving holes in said lock core and automatic safety devices for stopping said machine when the filling of said lock core is completed.

31. A lock filling machine embodying a core holding device arranged to receive a lock core, means for cutting stacks of tumbler pins to conform to a predetermined lock combination, a pin delivery arm for moving said stacks of tumbler pins into alignment with a hole in said lock core, spring forming means, a spring delivery arm for moving springs into alignment with said hole in said lock core, cap supply means, cap delivery means for moving a cap into alignment with said hole in said lock core and a loading plunger for loading a stack of pins, a spring, and a cap into said aligned hole in said lock core.

32. A lock filling machine embodying a core holding device arranged to receive a lock core, means for cutting stacks of tumbler pins to conform to a predetermined lock combination, spring supply means, cap supply means, devices for loading a stack of said pins, a spring and a cap into a tumbler pin receiving hole of a lock, core and means for automatically moving said lock core to bring the tumbler pin receiving holes successively into line with said loading devices.

33. An automatic lock filling machine embodying key holding means arranged to receive keys having notches therein, means for cutting stacks of tumbler pins, tumbler pin measuring means including devices arranged to engage within notches in each key whereby the length of successive tumbler pins in a stack will be determined by different key notches, a core holding device arranged to receive a lock core having tumbler pin receiving holes therein, spring supply means, cap supply means, loading means for loading a stack of said tumbler pins, a spring and a cap into a tumbler pin receiving hole in a lock core, devices for moving said key holding means to cause said pin measuring devices to engage within different notches in said keys and mechanism on said key holding device for governing the movement of said core holding device.

34. In a machine of the class described, pin measuring and cut off devices, embodying a rotatable collet arranged to grasp pin slugs, a rotatable stepped collar for positioning said pin slugs in said collet, means governed by the shape of keys for determining the adjustment of said stepped collar and means for cutting off tumbler pins from the pin slugs held in said collet.

35. In a lock filling machine, a collet arranged to grasp and hold pin slugs, a rotatable stepped collar for positioning said pin slugs in said collet, means governed by the shape of keys for determining the position of said stepped collar, means for cutting off tumbler pins from said pin slugs, the length of said tumbler pins being determined by the position of said stepped collar, and means for loading said cut off tumbler pins into a lock.

36. In a lock filling machine, rotatable collet arranged to grasp and hold pin slugs, means for successively opening and closing said collet, a rotatable stepped collar, means governed by said collar for engaging the ends of pin slugs held in said collet, yielding means for urging said pin slugs toward said stepped collar when said collet is open, key controlled means for determining the position of said stepped collar, means for cutting off tumbler pins from said pin slugs, and means for loading said cut off tumbler pins into a lock.

37. In a lock filling machine a rotatable collet arranged to grasp and hold pin slugs, means for successively opening and closing said collet, cutter means arranged to pass

- the end of said collet during the closed period of the same, means for urging a pin slug outwardly in said collet, positioning means located adjacent the end of said collet 5 for limiting the outward movement of a pin slug, devices governed by the shape of keys for automatically adjusting said positioning means and means for loading cut off tumbler pins into a lock.
- 10 38. In a lock filling machine a rotatable collet arranged to grasp and hold pin slugs, means for successively opening and closing said collet, cutter means arranged to pass the end of said collet during the closed 15 period of the same, to cut off tumbler pins from the end of said pin slugs, yielding means for urging a pin slug outwardly in said collet, a stepped collar opposite the end of said collet for determining the position 20 of a pin slug in said collet, key holding means, devices governed by the shape of keys that are inserted in said key holding means for determining the position of said stepped collar and means for loading stacks 25 of cut off pin slugs into locks.
39. In a lock filling machine a collet, means for rotating said collet, cam controlled means for opening and closing said collet at intervals, a spring pressed plunger disposed within said collet, cam controlled means for retracting said plunger at intervals, means for feeding pin slugs into said collet, said pin slugs projecting from the end of said collet and a cutter operating 35 in close proximity to the end of said collet to cut off tumbler pins from the end of said pin slugs.
40. In a lock filling machine a collet, means for rotating said collet, means for supplying pin slugs to said collet, yielding means for urging said pin slugs outwardly in said collet, devices for retracting said yielding means at intervals, means for opening and closing said collet at intervals, a 40 measuring pin disposed opposite the end of said collet for determining the amount that a pin slug may project from said collet, key governed means for adjusting the position of said measuring pin and a cutter for cutting off tumbler pins of measured length 45 from pin slugs that protrude from said collet.
41. In a lock filling machine a rotatable collet arranged to grip a pin slug, means for causing said collet to release its grip on said pin slug at intervals, means urging said pin slugs outwardly in said collet, means for cutting off portions of said pin slugs that protrude from said collet, a measuring pin arranged to be moved into alignment with said collet to limit the distance 50 of protrusion of a pin slug from said collet, means governed by the shape of keys for determining the position of said measuring
- pin and means for loading pins that are cut 65 from said pin slugs into a lock.
42. In a lock filling machine a rotatable collet, means for opening and closing said collet, a pin slug magazine, a slug delivery arm arranged to receive pin slugs from said 70 magazine and move said slugs into alignment with said collet, a spring pressed slug loading driver on said slug delivery arm for delivering said pin slugs into said collet, a stack delivery arm having a tumbler pin 75 receiving hole arranged to be moved into alignment with said collet, a cutter operable between said stack delivery arm and the end of said collet, a measuring pin arranged to enter the pin receiving hole in said stack delivery arm to determine the length of successive tumbler pins that are cut from 80 said pin slugs, and means for loading stacks of tumbler pins into locks.
43. In an automatic lock filling machine, 85 pin measuring and cut off means embodying pin slug holding devices, pin cut off devices, an escapement drum, a key holder arranged to have keys inserted therein, movable arms arranged to be positioned by said keys for stopping said escapement drum and means governed by the position of said escapement drum for determining the length to which 90 said pins are cut.
44. In an automatic lock filling machine 95 pin measuring and cut off means embodying pin slug holding devices, pin cut off devices, an escapement drum, friction means for driving said escapement drum, a key carriage, a key holder on said key carriage 100 arranged to have keys inserted therein, lever arms mounted on said key carriage and arranged to govern the movement of said escapement drum, means engaging notched edges on said keys for determining the positions of said lever arms, and means connected with said escapement drum for determining the length to which said pins are 105 cut.
45. In an automatic lock filling machine, 110 a rotatable collet arranged to grasp and hold a pin slug, cutter means arranged to pass the end of said collet at intervals, yielding means for urging a pin slug outwardly in said collet, a stepped collar for positioning pin slugs in said collet, an escapement drum connected with said stepped collar, pins on said escapement drums, a key carriage, lever arms on said key carriage for engaging the pins on said escapement drum to stop said stepped collar, a key holder arranged to have notched keys inserted therein and means engaging with the notched portions of said keys for governing the positions of 115 said lever arms.
46. In an automatic lock filling machine 120 pin measuring and cut off means embodying pin slug holding devices, a pin cutter, an

escapement drum, means governed by the position of said escapement drum for determining the length to which said pins are cut, a key carriage, a key holder arranged to have keys inserted therein, escapement drum stop means arranged to be positioned by engagement with the notched portions of said keys and means for moving said keys relative to said escapement drum stop means.

47. In an automatic lock filling machine, pin measuring and cut off means embodying pin slug holding devices, a pin cutter, an escapement drum, stop members projecting from said escapement drum, means governed by the position of said escapement drum for determining the length to which tumbler pins are cut, a movable key carriage, levers on said key carriage arranged to be engaged by the stop members on said escapement drum, a key holder therein, keys carriage to release said escapement drum from a previously engaged lever arm and means for preventing rotation of said escapement drum while said key carriage is moved away from said escapement drum.

48. In an automatic lock filling machine, pin measuring and cut off means embodying pin slug holding devices, tumbler pin cut off means, an escapement drum, friction means for rotating said escapement drum, means connected with said escapement drum for determining the length to which said tumbler pins are cut, a key carriage, a key holder arranged to have keys inserted therein, escapement drum stop means arranged to be positioned by engagement with the notched portions of said keys, means for moving said keys relative to said escapement drum stop means and means for withdrawing said escapement drum stop means from engagement with said keys while said keys are being moved relative to said escapement drum stop means.

49. In a lock filling machine of the class described, a key carriage, a key holder movable with respect to said key carriage, escapement means controlling movement of said key holder away from said key carriage, manually controlled quick return means for rendering said escapement means in operative and permitting a quick return of said key holder toward said key carriage and automatic devices for preventing the operation of said quick return means when said machine is in operation.

50. In a lock filling machine of the class described, a key carriage, a key holder movable on said key carriage an escapement con-

trolling the movement of said key holder with respect to said key carriage manually operated quick return means for rendering said escapement inoperative and permitting a quick return movement of said key holder with respect to said key carriage, stop means governing the starting and stopping of said machine and safety devices connected with said stop means for preventing the operation of said quick return means when said machine is in operation.

51. In a lock filling machine of the class described a key holder arranged to have keys inserted therein, pin measuring means including key engaging devices means for moving said keys relative to said key engaging devices, and means for withdrawing said key engaging devices from contact with said keys while said keys are being moved.

52. In a lock filling machine of the class described, a key holder arranged to have keys inserted therein to determine the combination of a lock and means for locking said keys in said key holder.

53. In a lock filling machine of the class described, a key holder having means for the reception of a plurality of keys, and devices for locking said keys in said key holder while said machine is in operation.

54. In a lock filling machine of the class described, a key holder having keyways for the reception of a plurality of keys, automatic stop means governing the starting and stopping of said machine, and devices connected with said automatic stop means for locking said keys in said key holder when said automatic stop means is in a withdrawn position and releasing said keys when said automatic stop means is in an engaged position.

55. In a lock filling machine of the class described a key holder having a plurality of keyways for the reception of keys, automatic stop means governing the starting and stopping of said machine, and selective devices connected with said automatic stop means for preventing the starting of said machine except when keys are inserted in predetermined keyways.

56. In a lock filling machine, a frame, means on said frame for cutting off tumbler pins to predetermined lengths and loading the same into locks, cams for operating said means, a cam drum carrying said cams and means including a friction clutch for driving said cam drum.

FRANK ELLISON BEST.
